UNITED STATES PATENT OFFICE.

LEON LAPIDUS, OF BROOKLYN, NEW YORK.

DESIGN FOR AN AUTO REAR SIGNAL LAMP.

Application filed August 31, 1922. Serial No. 3,608. Term of patent 7 years.

To all whom it may concern:

Be it known that I, LEON LAPIDUS, a citizen of the United States, residing at 311 Arlington Avenue, in the borough of Brooklyn, county of Kings, city and State of New York, have invented a new, original, and ornamental Design for an Auto Rear Signal Lamp, of which the following is a specification, reference being had to the accompanying drawing, forming part thereof.

Fig. 1, is an elevation of the face of my rear auto signal lamp;

Fig. 2, is a rear elevation; and

Fig. 3, is a side elevation thereof, showing my new design, the colored portions thereof being represented symbolically.

I claim:

The ornamental design for an auto rear signal lamp, as shown.

LEON LAPIDUS.
